UNITED STATES PATENT OFFICE.

ARVILLE H. PETIT, OF HUNTINGTON, WEST VIRGINIA.

AUTOMATIC TRAP-NEST.

1,345,229.

Specification of Letters Patent. Patented June 29, 1920.

Application filed November 23, 1917. Serial No. 203,563.

To all whom it may concern:

Be it known that I, ARVILLE H. PETIT, a citizen of the United States, residing at Huntington, in the county of Cabell and State of West Virginia, have invented certain new and useful Improvements in Automatic Trap-Nests; and I do hereby declare the following to be a full, clear, and exact description of the invention, such as will enable others skilled in the art to which it appertains to make and use the same.

This invention relates to improvements in automatic trap nests.

The object of this invention is to improve the construction of automatic trap nests so as to render the nest movable under the weight of the hen so as to close the entrance to the nest and prevent other hens from entering the nest when occupied.

A still further object of this invention is to provide an automatic trap nest of this character, which will be simple, practical and comparatively inexpensive in construction and one that can be manufactured and sold at a low cost.

With these and other objects in view, the invention consists in the novel combination and arrangement of parts hereinafter more fully described and set forth in the claim 30 hereto appended.

In the drawings—

Figure 1 is a front elevation of the automatic nest as made in accordance with this invention,

Fig. 2 is an end elevation of the same,

Fig. 3 is a vertical longitudinal sectional view of the nest,

Fig. 4 is a transverse vertical sectional view taken on the line 4—4 of Fig. 3,

Fig. 5 is a fragmentary transverse sectional view of a modified form of the device.

Fig. 6 is another fragmentary sectional view illustrating the manner in which the upper pivoted nest is held stationary when the modified form of the device is in use.

Like numerals of reference designate corresponding parts in all the figures of the drawings.

Referring to the drawings, the numeral 5 indicates a housing in its entirety and it comprises a rear wall 6, front wall 7 and end walls 8 and 9 respectively. The end walls 8 and 9 are provided adjacent their upper ends 55 with the transverse openings 10 which communicate with the interior of the housing

and form ventilation openings to permit the interior of the housing to be aired. The end wall 8 is provided below its ventilation opening 10 with a rectangular opening 11, which 60 opening constitutes an entrance whereby a hen may enter the housing. The housing 5 is supported by the legs 12 which are secured to the ends thereof, and the front legs have pivotally secured thereto supports 13. The 65 supports 13 are pivotally secured to the front legs intermediate their ends as at 14 and when in a horizontal position as illustrated in Fig. 2 they support a suitable roost or rest 15 upon which the hens step prior to 70 their entering the housing.

A partition 16 is secured to the front and rear walls of the housing and extends substantially one-half of the height of the interior thereof, thus dividing the interior at 75 the lower portion thereof into separate compartments.

A pair of nests comprising end walls 17, and side walls 18, which side walls have secured thereto a suitable body 19 so as to form 80 the bed of the nests, is pivotally secured on a rod 20 which extends longitudinally through the end walls 8 and 9 respectively, thus pivotally securing the nests 17 on the interior of the housing 5 at the bottom thereof. The partition 16 is provided on its opposite faces with spaced eyes 21 through which extend flexible members 22, one end of each flexible member being connected as at 23 to one end wall of the corresponding nest 90 17 at the rear end thereof and the opposite end of the flexible member extending outwardly through the front wall 7 and being connected to the lower end of a latch 24 as at 25. The latches 24, (two in number) are 95 each pivotally secured intermediate their ends as at 26 to diagonal braces 27 which are secured to the front wall 7 of the housing. The front wall of the housing is provided with a pair of relatively spaced entrance openings 28 which are adapted to be closed by the doors 29 pivotally secured to the front wall as at 30. The doors are provided with extending tongues 31 which are adapted to rest upon the notched portions 100 32 formed in the front edges of the latches 24. Thus it can be seen that the doors may be held in raised position so that a hen may jump upon the rest 15 and enter either one of the nests 17 through the openings 28. 110 The weight of the hen in the nest 17 will rock the same about rod 20 so as to tension

member 22 pulling the latch rod 24 inwardly, thus moving member 32 from under the extending tongue 31 of the door and permitting it to drop, so as to close the entrance to the nest and prevent the hen from being molested while occupying the said nest. As will be understood, the door is raised manually to release the hen.

When it is desired to use the nest 17 as an ordinary stationary nest, the door 29 is raised until the tongue 31 engages between the lugs 32^a secured to the front wall 7 and braces 27, thus leaving the opening 28 completely uncovered to permit the entrance of hens when desired. The raising of the doors releases the latches and flexible member 22, whereby the nests 17 are converted from trap nests into ordinary stationary nests.

A third nest designated in its entirety by the numeral 33 includes side rails 34 which have their inner ends enlarged as at 35 and provided with curved bottom edges 36 the ends of which rails are connected by a cross brace or connecting bar 37, and connecting bar 38 connecting the other ends of the rails and depending therefrom, the purpose of which will be hereinafter more fully described. A foraminous member 39 is secured to the lower curved edges of the enlarged ends 35 of the side rails thus forming a nest proper, and the smaller portions have secured therebetween a bottom wall 40 which is spaced from the edge of the member 39. An inclined central brace 41 is secured between the enlarged portions of the side rails 34 so as to form a nest and a platform. A transverse pivot rod 42 is journaled in the front and rear walls of the housing and through the side rails 35 of the nest 33, thus pivotally securing the nest in the housing. In normal position, the smaller ends of the side rails 34 are in the position illustrated in full lines in Fig. 3 thus locating the upper edge of the depending bar 38 closely adjacent the bottom wall of the opening 11 whereby a hen may readily enter nest 33 so as to rock the side rails on rod 42 thus raising the depending bar 38 into such a position as to close the opening 11 and permit the hen to occupy the nest unmolested.

The front and rear walls of the housing are provided with spaced guides 43 which are arranged in parallel relation and are adapted to receive therein the auxiliary partition member 44 which divides the nest 33 into separate compartments and serves to hold the nest in a horizontal position as illustrated in dotted lines. There is provided adjacent one side of the opening 11 a pivoted

latch 45 which is pivotally secured as at 46, 60 and has its free end provided with a hook 47 which is adapted to engage the bottom or lower edge of the depending bar 38 to hold the nest 33 in a substantially horizontal plane, this latch being operable through a slot provided through side wall 8 for this purpose. To provide entrance openings to the nests now formed by the partition 44 there is hingedly secured to the rear wall of the housing a cover 48, which, when the auxiliary partition is in position, is adapted to be held in a raised position as illustrated in Fig. 5.

When it is desired to make the nest 33 a trap nest, it is only necessary to remove the partition 44 and close the cover. The nest is then rocked by gravity into the position illustrated in Fig. 3, giving entrance to the housing through the opening 11 in the end wall 8. Upon the hen entering the opening 11 it steps upon the bottom 40, and then into the bottom 39 of the nest 33, and the weight of the hen will cause the nest proper to rock downwardly on its pivot rod 42, thus raising the bar 38, so as to close the opening 11 and prevent entry of other hens so long as the nest is occupied.

A plate 49 is pivotally secured as at 50 to the wall 8 and is adapted to be moved to such a position as to hold the latch 45 out of engagement with the bar 38 of the nest 33, thus permitting the nest to be used as a trap nest to close the entrance opening 11 in the end wall 8.

Having thus described my invention what I claim is:

A hen's nest including a housing having an entrance way, a door for closing said entrance way, an arm formed on said door and projecting beyond the same and pivoted to the housing laterally of the entrance way, a shoulder formed on the door at a point opposite from that of the arm, a nest pivoted in the housing in a plane below the entrance way, an inclined latch bar pivoted to the housing and engaging the shoulder for holding the door in an open position, and a flexible element connected to the latch bar and slidably connected to the housing in a plane above the nest and connected to said nest at its rear end to support said nest in an inclined plane.

In testimony whereof I affix my signature in presence of two witnesses.

ARVILLE H. PETIT.
